UNITED STATES PATENT OFFICE.

GEORGE INNES AND JAMES H. PRALL, OF PHILADELPHIA, PENNSYLVANIA.

GRAIN-SHOCKER.

1,346,542.

Specification of Letters Patent. Patented July 13, 1920.

Application filed April 4, 1917, Serial No. 159,614. Renewed December 4, 1919. Serial No. 342,475.

To all whom it may concern:

Be it known that we, GEORGE INNES and JAMES H. PRALL, citizens of the United States, and residents of Philadelphia, Pennsylvania, have invented certain Improvements in Grain-Shockers, of which the following is a specification.

Our invention relates to grain shocking devices; and the object of our invention is to provide a structure arranged to travel with the harvester and binder, and in such relation to the binder that the mechanism carried by our improved shock-forming structure lies in proper position to pick up bundles from a platform to which they are delivered by the binder and present the same to a suitable bundle-carrying basket or crib suitably connected to the rear of our improved structure in which the shocks, subsequently deposited upon the ground, are formed.

Our invention includes a frame with suitable running gear whereby it may traverse the ground; such running gear providing the necessary power to operate the bundle-gripping and lifting mechanism, and mechanism to actuate the crib or basket in which the shock is formed to its receiving position.

At the forepart of the supporting frame to which the running gear is attached, a vertical frame is provided to which is connected the bundle-lifting means whereby bundles or sheaves may be transferred from the platform to the crib or basket.

These and other features of our invention, including the various details embodied in our improved apparatus, are more fully disclosed hereinafter, reference being had to the accompanying drawings, in which:

Figure 1, represents a plan view of our improved shocking machine.

Fig. 2, is a side elevation of the same showing the crib or basket in the raised or active position ready to receive bundles or sheaves; the mechanism for lifting the latter from the platform being shown in the position assumed after delivery of the bundles or sheaves to said basket.

Fig. 3, is a similar elevation showing the bundle-gripping mechanism in picking-up position.

Fig. 4, is a front elevation of the machine, partly in section, on the line IV—IV, Fig. 2.

Fig. 5, is a vertical sectional view on the line V—V, Fig. 2, looking toward the rear of the machine.

Fig. 6, is a sectional view illustrating a detail of our invention.

Fig. 7, is a view of a modified detail within the scope of our invention.

Fig. 8, is a sectional view on the line VIII—VIII, Fig. 7, and Figs. 9, 10 and 11, are diagrammatic views illustrating the manner in which a pair of bundles or sheaves are handled.

The running gear and frame, which may be rectangular in plan view, comprises side members 1, with suitable cross-bars 2, connecting the same; a shaft or axle 3, being provided, suitably hung in bearings carried by the frame, and having wheels 4, at its opposite ends; one or both of which may be provided with spurs 5, to increase the traction. The forward end of the frame is preferably provided with a bearing 6, for a bracket 7, carrying a caster wheel 8.

At the rear of the running gear or frame, we provide a crib or basket 9, having connecting members 10, which are coupled to the running gear by links 11. The basket or crib may be maintained in the elevated position, as shown in Figs. 2, 3 and 5, by means of a link arm 12, which may be arranged to overlie a counter-shaft 13, which may be mounted directly over the axle 3; said lever being connected at its free end to a chain 14, lying in engagement with a toothed segment 15, carried by the shaft 13; which segment in turn is operatively connected with a torsion spring 16, on said shaft; having its opposite end connected at 17, to a portion of the frame. The torsion spring operates to restore the crib or basket to the elevated position through the mechanism indicated, after a load of bundles or sheaves constituting a shock has been deposited upon the ground.

As shown in Figs. 2, 3 and 5, the basket is retained in the position indicated by reason of the fact that the link arm 12, is bent so that its end in connection with the chain 14, extends past the center around which said chain moves. To overcome this condition, we provide a connection in the form of a cord or chain 15^a, attached to a pulley 15^b, secured to the shaft 13, and attached at its opposite end to a lever (not shown) convenient to the operator or driver of the harvester.

At the front of the running gear frame, a vertically disposed frame 18, is provided, comprising side members 19, connected at

the upper portion by a plate 20, of special construction, more particularly described hereinafter and by a cross bar 21. The side bars of this frame are preferably braced from the running gear frame by struts 22, which may extend forwardly beyond the front of the frame 18, and provide a support for a shaft or bar 23, for a purpose to be described; additional supporting and bracing means for said shaft 23, extending from the vertical frame in the form of bracket struts 24.

Carried by the axle 3, of the machine is a gear wheel 25, which may be thrown into and out of operative engagement by a clutch 26, so as to be driven by the axle when desired, and this gear wheel may mesh with a horizontally disposed gear wheel 27, suitably journaled on the running gear frame and serving as a face plate or pitman to operate a bevel gear segment 28, which may be horizontally movable on a vertical axis 29; a connecting bar 30, extending between the same and the operating gear wheel 27; said gear segment 28, meshing with a gear segment or wheel 31, on a horizontal shaft or spindle 32, and to which gear segment is attached a connection for a substantially vertically movable member 33, designed to actuate means whereby the member for lifting the sheaves or bundles with which the basket is to be filled may be properly operated.

The means for lifting the bundles or sheaves from the platform of the shocker, indicated at 34, comprise a rod or bar 35, connected by means of a universal joint 36, to the shaft 23, at the front of the machine; said rod or bar 35, being adapted to a curved slot 37, in the plate 20, carried by the vertical frame 18, and being actuated to effect the lifting and depositing operation by the vertically movable member 33, controlled by the bevel gear wheel or segment 31; the vertically movable member 33, having a slotted upper end 38, through which said rod 35, passes.

The outer or free end of the rod 35, carries a hub 40, in which is mounted a hollow stem 41, carrying a bracket frame 42, extending beneath the rod and upon which is journaled a pinion 43, engaged by a rack 44, for a purpose to be described.

Depending from the bracket frame 42 beneath the rod are a pair of supports 49, for hooked arms 50, the position of which may be relatively fixed with respect to the rest of the structure. In addition, the bracket frame carries open frames 51, which, additionally, may be connected together at the center by a bolt 52, on which is journaled a bell crank lever 53.

The forward ends of the hooked bars 50, are connected together at 54, and pivotally connected to said hooked bars 50, at the

points 55, are the laterally movable hook bars 56, which lie outside the hooked bars 50, and are provided with substantially laterally disposed arms 57; the outer ends of which are connected together by a spring 58, the function of which spring is to spread said arms 56, to the limit of their movement within the frames 51; the latter being provided with lugs 59, to hold them in such outward position. As so held, they are in position to descend upon and grasp a pair of sheaves or bundles. In this act, the ends of the hook arms 56, contact with the platform 34, and release themselves from the engagement of the lugs 59, of the frames 51. At the same time, the movement of the bar 35, to carry this bundle-lifting mechanism into grasping position has moved with reference to a sleeve 60, slidable thereon, to which is attached at 61, a cord 62, passing around a sheave 63, at the end of the rod; the opposite end of said cord being attached at 64, to the bell crank lever 53, thereby lifting said bell crank lever so that the hook 65, may engage the same and support it against the tension of the spring 66, until the hook arms 56, are released. Immediately they are released, as before described, the spring 66, which is connected to the loops 67, attached at 68, to the arms 57, actuates said arms 57, to cause the arms 56, to be thrown in at their rear ends and thereby grip the bundles picked up.

When the bundle-gripping device is moved to picking-up position and into engagement with the platform 34, as shown in Fig. 3, an extensible rod 69, which is connected at one end to the sleeve 60, and at the opposite end to the vertical frame 18, and contains a compressible spring 70 within a sleeve 71, elongates under tension of the spring 66; the latter being connected to the sleeve 60, by means of the cord 62, and bell crank lever 53; such elongation contracting the spring 70. When the bar 35, rises with the bundle-lifting device in engagement with sheaves lifted from the platform 34, which action swings the bundle-gripping devices to the delivery position shown in Figs. 1 and 2, the spring 70, within the sleeve 71, of the rod 69, lengthens and takes up all slack of said rod between its connections with the end frame 18, and the sleeve 60.

As the bundle-gripping means are raised by the vertically movable member 33, which operates the rod 35, the pinion 43, will be turned by its engagement with the rack 44, to an extent sufficient to reverse the position of the bundle-gripping means and cause the stem of the hook 65, to swing its projecting end 72, into engagement with a lug 73, carried by the rod 35, thereby releasing or spreading the bundle-gripping mechanism and permitting the bundles to drop into the crib or basket from said gripping device

when the latter is in the position shown in Fig. 2. This rod 35, is restrained from excessive movement by means of a spring 75, connected to the same and to the vertically movable member 33, which operates it, and the latter is provided with a spring 76, between a collar 77, carried thereby and a sleeve 78, slidable horizontally on the cross-bar 21, of the vertical frame 18; said sleeve 78, having another sleeve 79, pivotally connected thereto, through which the vertically movable member 33, is free to slide in its movements.

As shown in Fig. 4, the rod 35, is disposed in the curved slot 37, in the plate 20, carried by the vertical frame 18, at the front of the machine; the vertically movable member 33, being shown in the position it assumes when its connection with the gear wheel or gear-segment 31, moves in the direction of the arrow x . If further movement of said member 33, occurs, the rod 35, will be lowered in the left-hand portion of the slot 37. Upon the return movement of the gear-segment 31, in the direction of the arrow y , the member 33, will be raised, lifting the rod 35, until a roller 80, carried by said member enters a notch 81, in the plate 20, which serves as a bearing or fulcrum point for the same so that the rod 35, may be swung to the opposite side of the slot 37, and upon continued movement of the gear-segment in the direction of the arrow y , the rod 35, will be carried down the right-hand portion 35 of said slot 37, and in such movement lower the bundle-gripping device to the platform 34, to pick up bundles or sheaves for subsequent delivery to the basket or crib 9, in which the shocks are formed.

As the rod 35, lowers in the right-hand portion of the slot 37, the spring rod 69, elongates, and through the medium of the cord 62, tension is applied to the spring 66, through the bell-crank lever 53, so that the moment the hooks 56, are displaced from the retaining lugs 59, by the engagement of such hooks with the platform 34, they will be drawn in by the operation of said spring 66, to grip the bundles or sheaves and hold them in the position shown in Fig. 10.

In lieu of the mechanism for lifting the basket, illustrated in Figs. 1, 2 and 3, in which a lever 12, and chain 14, are shown in engagement with a toothed segment 15, carried by a shaft 13, we may provide the structure shown in Figs. 7 and 8, in which a segmental sheave 85, having a hollow center 86, is shown. In this instance, a chain 14^a, is shown as connected at 87, to the basket; thence passing through the hollow portion of the segmental sheave and being connected at 88, to one end of the same; the shaft 13^a, having a trunnioned connection with said segmental sheave. This structure will be operated in a manner substantially, if not ex-

actly, similar to that described with reference to the structure illustrated in Figs. 1, 2 and 3; a pulley 15^b, being formed integral with the segmental sheave and having a cord or chain 15^a, attached thereto in the usual manner for operation by the attendant, which cord will pass around the guide wheel 90, in the usual manner.

The cord or chain 15^a passes from the pulley 15^b around a guide wheel or idler 90, disposed adjacent the front of the main frame; thence extending to operative means (not shown) adjacent or convenient to the driver of the harvester whereby it may be readily operated at the desired time to trip the basket connection and permit the latter to lower and deliver a shock.

The wheel 25 hereinbefore referred to is loose on the shaft or axle 3, so that when the clutch 26 is out, said wheel will remain idle during any movement of the shocker. In the present instance, the clutch carries the usual yoke member 91, to which is pivotally connected one arm 92 of a bell crank lever 93, journaled in a bracket 94, carried by the frame; the opposite end 95, of said lever being connected to a rope or cord 96 passing around a guide or idler pulley 97, and thence extending to suitable operative means mounted adjacent the driver or operator of the harvester. The clutch is of such a character that it must be held in operative position by pulling the cord 96; holding of the same being effected by suitable means adjacent the operator (not shown). When this retaining means for said cord 96, is released, the clutch will automatically release itself upon continued movement of the shocking device.

Formed integral with the hub 40, having the hollow stem 41, is a housing 45, in which the rack 44, is free to slide; such housing being slotted in the side for movement of a projection 46, carried thereby, which projection is pivotally connected to a rod 47, the outer end of which is universally connected at 48, to the rock shaft 23, carried by the vertical frame 18, so that as movement is imparted to the rod or shaft 35, to swing the same from the platform to delivery position, and vice versa, the rod 47, will automatically operate the rack 44, and thereby turn the gear wheel 43, and effect the operation of the parts controlled thereby.

In the operation of picking up the bundles, the fingers 50, engage the same on the platform 34, passing into the body thereof, (see Fig. 9), and upon continued movement of the bundle-grasping mechanism in the downward direction, the hook arms 56, contact with the platform and release themselves so that the spring 66, may cause them to grasp the bundles. In this act, the bundles are brought together at one end of the same, while their opposite ends are spread

apart, (see Fig. 10), making it substantially easy for them to slide into the basket on both sides of the central partition of the basket after they have been reversed, (see Fig. 11).

It will be understood that when the rod 35, is being moved by the vertically movable member 33, down the right-hand side of the slot 37, in the plate 20, that the sleeve 60, 10 will slide on said rod 35, and elongate the spring 66, thereby placing the same under tension for the necessary operation of the hook arms 56, when they are brought to bundle-gripping position.

15. While we have shown a certain arrangement of gearing whereby the bundle-handling device may be operated, it will be understood that any gearing interposed between the main driving shaft and in operative engagement with the wheel 25, or its 20 equivalent may be employed to impart proper motion to the vertically movable member 33, and thereby actuate the rod or shaft 35, to the end of which the bundle-grasping means are connected.

We claim:

1. In a shocking machine, the combination of a frame, a shock-forming crib or basket flexibly connected to said frame, a 30 shaft, a cam segment carried by the shaft, a member connected to the basket and passing over said shaft; said member being connected at its opposite end to the cam segment, and tension means carried by the shaft and operatively connected between said cam segment and the frame whereby said basket may be returned to its elevated position when relieved of the weight of the shock.

2. In a shocking machine, the combination of a frame, a shock-forming crib or basket flexibly connected to said frame, a shaft, a cam segment carried by the shaft, a flexible member connected to the basket and the cam segment and passing over said 45 shaft and around the cam segment, and tension means carried by the shaft and operatively connected between said cam segment and the frame whereby said basket may be returned to its elevated position when relieved of the weight of the shock.

3. In a shocking machine, the combination of a frame, a shock-forming crib or basket flexibly connected to said frame, a shaft, a cam segment carried by the shaft, a lever connected to the basket and passing over said shaft, a flexible member connecting the lever and the cam segment, and tension means carried by the shaft and operatively connected between said cam segment and the frame whereby said basket may be returned to its elevated position when relieved of the weight of the shock.

4. In a shocking machine, the combination of a frame, a shock-forming crib or basket flexibly connected to the same, a

shaft, a cam segment carried by the shaft, a flexible connection overlying said shaft and connecting the cam segment with the frame; and a spring operatively connected between said cam segment and the frame 70 whereby said basket may be returned to its normal elevated position when relieved of its weight.

5. In a shocking machine, the combination of a frame, a shock-forming crib or basket flexibly connected to the same, a shaft, a cam segment carried by the shaft, a lever connected to the basket and overlying said shaft, a chain engaging the cam segment and connecting the same with the 80 lever, and a spring operatively connected between said cam segment and the frame whereby said basket may be returned to its normal elevated position when relieved of its weight.

6. In a shocking machine, the combination of a frame, a shock-forming crib or basket flexibly connected to the same, a shaft, a cam segment carried by the shaft, a flexible member connecting the basket and 90 the cam segment, a spring between said cam segment and the frame whereby said basket may be returned to its normal elevated position when relieved of its weight; said flexible member and cam segment acting to lock 95 the basket in the elevated position, and means for tripping the cam segment.

7. In a shocking machine, the combination of a frame, a shock-forming crib or basket flexibly connected to the same, a shaft, a cam segment carried by the shaft, a lever connected to the basket and passing over said shaft, a flexible member connecting the lever and the cam segment, a spring 105 acting upon said shaft to hold said cam segment with the basket in the normal position; said lever acting to lock the basket in such position, and means for tripping the lever.

8. In a shocking machine, the combination of a frame, a shock-forming crib or basket flexibly connected to the same, a shaft, a cam segment carried by the shaft, a lever connected to the basket and passing over said shaft, a flexible member connecting the lever and the cam segment, a spring between said cam segment and the frame whereby said basket may be returned to its normal elevated position when relieved of its weight; said lever acting to lock the 120 basket in the elevated position, and means for tripping the lever.

9. The combination, in a shocking machine, of a horizontal frame, running-gear therefor, a substantially vertical structure 125 at the front of said horizontal frame, a rod or bar pivotally connected at the upper portion of said vertical structure, a vertically movable member for operating said rod or bar, a pivotal mounting upon which said 130

vertically movable member may swing while it is raised and lowered, bundle-gripping mechanism carried at the opposite end of said rod or bar, and means controlled by the running gear for operating said vertically movable member.

10. The combination, in a shocking machine, of a horizontal frame, a vertical frame at the front of the same, running-gear to which said frames are operatively connected, a rod or bar pivotally connected to the upper part of said vertical frame, a vertically movable member for operating said rod or bar, a pivotal mounting upon which said vertically movable member may swing while it is raised and lowered, bundle-gripping mechanism carried at the opposite end of said rod or bar, means controlled by the running-gear for operating said vertically movable member, and means on the vertical frame for guiding the upper end of said vertically movable member.

11. The combination, in a shocking machine, of a main frame, running-gear supporting the same, a vertically disposed structure at the front of said frame, a rod or bar pivotally connected to the upper portion of said vertical structure, a vertically movable member for actuating said rod or bar, bundle-gripping means carried at the opposite end of said bar, means actuated by the running-gear for operating said vertically movable member, and a slotted plate carried by said vertically disposed structure for controlling the position of the rod or bar at its bundle-gripping end as it is moved by the vertically movable member.

12. The combination, in a shocking machine, of a main frame, running-gear for the same, a vertical frame connected to the front of the main frame, a rod or bar pivotally connected to the upper portion of said vertical frame, a vertically movable member for actuating said rod or bar, bundle-gripping means carried at the opposite end of said bar, means actuated by the running-gear for operating said vertically movable member, a slotted plate carried by said vertically disposed structure for controlling the position of the rod or bar as the latter is moved by the vertically movable member, and a pivotal mounting upon which said vertically movable member may swing while it is raised or lowered.

13. The combination, in a shocking machine, of a frame, running gear for the same, a vertical support at the front of said frame, a plate carried thereby and having a U-shaped slot, a rod or bar pivotally connected to the upper portion of said support and movable in said slot, a vertically movable member for operating said rod or bar, means actuated by the running gear for operating said vertically movable member, and means whereby said member may fulcrum on the

plate below the slot and insure proper movement of the rod or bar to the opposite sides of said slot.

14. The combination, in a shocking machine, of a frame, running gear for the same, a vertical support at the front of said frame, a plate carried thereby and having a U-shaped slot, a rearwardly extending rod or bar pivoted to the upper portion of said vertical frame and movable in said slot, a vertically movable member for operating said rod or bar, gearing actuated by the running gear for operating said vertically movable member, and means whereby said member may fulcrum on the plate below the slot and insure proper movement of the rod or bar to the opposite sides of said slot.

15. The combination, in a shocking machine, of a frame, a rod capable of vertical and sidewise movement pivotally connected to said frame, a bundle-gripping device carried by said rod, a vertically movable member for actuating said rod, a pivotal mounting upon which said vertically movable member may swing while it is raised and lowered, means for effecting the raising and lowering of said vertically movable member, and means brought into action by the raising and lowering of the rod to shift the bundle-gripping device endwise with respect thereto.

16. The combination, in a shocking machine, of a frame, a rod capable of vertical and sidewise movement pivotally connected to said frame, a bundle-gripping device carried by said rod, a vertically movable member for effecting the raising and lowering of said rod, and a plate having a slot through which said rod passes; the walls of said slot coöperating with the vertically movable member to effect lateral shifting of the rod.

17. The combination, in a shocking machine, of a frame, a rod pivotally connected at one end to said frame and capable of vertical and lateral movement with respect to said frame, bundle-gripping means carried by said rod, a vertically movable member for effecting the raising and lowering of said rod, a plate having a slot through which said rod passes; the walls of said slot coöperating with the vertically movable member to effect lateral shifting of the rod, a pivotal mounting upon which said vertically movable member may swing while it is raised and lowered, and means for automatically shifting the position of the bundle-carrying mechanism with respect to the rod as the latter is moved in the vertical and lateral directions.

18. In a grain shocking machine, the combination of a frame having a vertical portion at the front of the machine, a rock shaft carried by said vertical portion, a rod or bar universally connected to said rock shaft, a vertically movable member for actuating

said rod or bar, means whereby said vertically movable member is actuated, rotatable bundle-gripping means carried by the opposite end of said rod or bar, said means including a bracket having a pivotal connection with the rod or bar, a pinion carried by said pivotal connection, a rack in engagement with said pinion, and a rod pivotally connected at one end to said rack and universally jointed at its opposite end to said rock-shaft; said rod or bar being operated vertically and laterally by the vertically movable member, and movement of the pinion to shift the bundle-gripping means taking place automatically by the action of the rack as the rod or bar is shifted.

19. The combination, in a shocking machine, of a main frame, running gear for the same, a vertically disposed portion at the front of said frame, a rod or bar pivotally connected to the upper end of said vertical frame, a vertically movable member for operating said rod or bar, a plate having a U-shaped slot for controlling the lateral position of said rod or bar, means actuated by the running gear for operating said vertically movable member, and means for effecting shifting of the vertically movable member with respect to the portions of said slot.

20. The combination, in a shocking machine, of a frame, running gear for the same, a vertically disposed portion at the front of said frame, a plate carried thereby and having a U-shaped slot, a rod or bar pivoted to the upper end of said vertical frame and movable in said slot, a vertically movable member for operating said rod or bar, means actuated by the running gear for operating said movable member, and means whereby said vertically movable member may fulcrum on the plate below the slot and insure proper movement of the rod or bar to the opposite sides of said slot, tension means for said vertically movable member, and lateral guiding means therefor.

21. In a shocking machine, the combination of a vertically disposed frame, a bar pivotally connected to the same, means for raising and lowering said bar, bundle-gripping mechanism carried by said bar, means for shifting said bundle-gripping mechanism with respect to the bar, a spring for holding said bundle-gripping mechanism in gripping position, means for releasing said spring, a pinion carried by the bundle-gripping mechanism, a rack for operating said pinion as the bundle-gripping device is raised and lowered, and means for shifting the position of said rack simultaneously with the lateral movements of said bar.

22. The combination, in a shocking machine, of a frame, a rod capable of vertical and sidewise movement pivotally connected to said frame, a bundle-gripping device carried by said rod, means for effecting the

raising and lowering of one end of said rod, means brought into action by the raising and lowering of the rod to shift the bundle-gripping device endwise with respect thereto, fingers which are spread as the gripping device is shifted, a spring connected to said fingers for closing them against a bundle, said spring being set as the bundle-gripping means are shifted, and means for releasing said spring.

23. In a shocking machine, the combination with the running-gear and a support therefor, of a vertically disposed frame, a rock-shaft carried by the upper portion of the same, a bar pivotally connected to said rock shaft, a vertically movable member for raising and lowering the opposite end of said bar, bundle-gripping mechanism carried by said end of the bar comprising a plurality of sets of hooks, one set of hooks occupying a relatively fixed position and the other set being movable with relation thereto, a pinion carried by said bundle-gripping mechanism, a rack in engagement with said pinion, a connecting rod pivotally connected at one end to the rack and universally jointed at its opposite end to said rock-shaft; said connecting rod effecting movement of the rack to actuate the pinion and shift the position of the bundle-gripping mechanism with respect to the bar carrying the same, and means for actuating said vertically movable member to raise and lower the bar and cause said bundle-gripping mechanism to engage and release a bundle or sheaf.

24. In a bundle-gripping device for shocking machines, the combination of a revolute frame, a support for the same, a plurality of sets of hooks, one set of hooks occupying a relatively fixed position and the other set being movable with relation thereto, means for raising and lowering said structure, a spring for effecting movement of one set of hooks in one direction, and means for applying tension to said spring.

25. In a bundle-gripping device for shocking machines, the combination of a revolute frame, a support for the same, a plurality of sets of hooks, one set of hooks occupying a relatively fixed position and the other set being movable with relation thereto, means for raising and lowering said bundle-gripping device, means for turning said structure end for end bodily simultaneously with its vertical movements, a spring for effecting movement of one set of hooks in one direction, and means for applying tension to said spring.

26. In a bundle-gripping device for shocking machines, the combination of a revolute frame, a movable support for the same, a plurality of sets of hooks, one set of hooks occupying a relatively fixed position and the other set being movable with relation thereto,

means for raising and lowering said structure, means for turning said structure end for end bodily including a pinion journaled in the support, a rack in engagement with 5 said pinion, and means for operating said rack.

27. In a bundle-gripping device for shocking machines, the combination of a revolute frame, a movable support for the same, 10 means for operating said support, a plurality of sets of hooks, one set of hooks occupying a relatively fixed position and the other set being movable with relation thereto, means for turning said structure end for 15 end bodily, including a pinion journaled in the support, a rack in engagement with said pinion, and means for operating said rack, a spring for moving one set of hooks, and means for applying tension to said spring.

28. In a bundle-gripping device for shocking machines, the combination of a revolute frame, a movable support for the same, a pair of hooks fixed with relation to said frame, a pair of hooks pivotally mounted 25 on said frame, a spring tending to hold said hooks in open position when the frame is in one position, means for turning said structure end for end bodily, a second spring for moving the pivotally mounted hooks, and 30 means for applying tension to said spring.

29. In a bundle-gripping device for shocking machines, the combination of a revolute frame, a support for the same, a plurality of sets of hooks, one set of hooks occupying a relatively fixed position, the other set being pivotally mounted and movable with relation thereto, means for holding the movable hooks out of action, means for turning said structure end for end bodily, said 40 movable hooks being moved thereby to gripping position, a spring for holding said set of hooks in gripping position, and means for applying tension to said spring.

30. In a shocking machine, the combination of a frame, a rock shaft journaled therein, a bar having a universal connection with said rock shaft, bundle-gripping means carried at the opposite end of said bar, a vertically movable member for shifting the position of said bar; said bundle-gripping means changing its position with 50 respect to the bar when the latter is shifted, and means including a pinion, a rack in engagement therewith, and a rod carrying said rack and connected to the rock-shaft, said rod being movable with the bar whereby said rack may actuate the pinion to effect the change in position of said bundle-gripping means.

31. In a shocking machine, the combination of a frame, a rock-shaft carried thereby, a bar pivotally connected to said rock-shaft; such connection permitting substantially 55 universal movement of the free end of said bar, bundle-gripping means carried there-

by, means for effecting movement of said bar; said bundle-gripping means occupying one position with respect to the bar when the latter is in one position with respect to the frame and another position when said 70 bar is shifted, a pinion carried by said bar and operatively connected to said bundle-gripping means, and a swinging rack in engagement with said pinion with its opposite end pivoted to the frame so that when the 75 bar is moved laterally the rack will move with it and actuate the pinion to shift the position of the bundle-gripping means.

32. In a shocking machine, the combination of a vertical frame, a bar universally jointed at the upper portion of said frame whereby up and down and lateral movement may be imparted to the free end of the same, bundle-gripping means carried by the free 80 end of said bar, means for effecting movement of said bar, a pinion carried by said bar; said pinion being operatively connected to said bundle-gripping means, and a swinging rack in engagement with said pinion with its opposite end pivotally connected 90 to the frame so that when the bar is moved laterally the rack will move with it and actuate the pinion to shift the position of the bundle-gripping means.

33. In a shocking machine, the combination of a frame, a rock-shaft carried thereby, a bar pivotally connected to said rock-shaft; such connection providing for substantially universal movement of the opposite and free end of said bar, bundle-gripping means carried by the free end of said bar, means for effecting movement of said bar; said bundle-gripping means occupying one position with respect to the bar when the latter is in one position with respect to the frame and another position when said 100 bar is shifted, a pinion operatively connected to said bundle-gripping means and carried by said bar, a swinging rack in engagement with said pinion, and a rod pivotally connected to the end of the rock-shaft and carrying said rack so that when the bar is moved laterally the rod and rack will move with it and actuate the pinion to shift the position of the bundle-gripping means. 105

34. In a shocking machine, the combination of a vertical frame, a rock-shaft carried by the upper portion thereof, a bar pivotally connected to said rock-shaft; such connection providing for substantially universal movement of the opposite and free end of said bar, bundle-gripping means carried by said free end of the bar, a vertically movable member operatively mounted with respect to said vertical frame; said member having 110 pivotal connection with said frame whereby it may swing in addition to its substantially vertical movements and impart universal movement to the end of said bar; said bundle-gripping means occupying one position with respect to the frame and another position when said bar is shifted, a pinion carried by said bar and operatively connected to said bundle-gripping means, and a rod pivotally connected to the end of the rock-shaft and carrying said rack so that when the bar is moved laterally the rod and rack will move with it and actuate the pinion to shift the position of the bundle-gripping means. 115

35. In a shocking machine, the combination of a frame, a rock-shaft carried thereby, a bar pivotally connected to said rock-shaft; such connection permitting substantially universal movement of the free end of said bar, bundle-gripping means carried there-

tion with respect to the bar when the latter is in one position with respect to the frame and another position when said bar is shifted, a pinion operatively connected to said bundle-gripping means and carried by said bar, a rack in engagement with said pinion, and a rod pivotally connected to the end of the rock-shaft and carrying said rack so

that when the bar is moved laterally the rod and rack will move with it and actuate 10 the pinion to shift the position of the bundle-gripping means.

In witness whereof we affix our signatures.

GEORGE INNES.
JAMES H. PRALL.
